(57) **CLAIM**

The ornamental design for a brush head for an electric toothbrush, as shown and described.

DESCRIPTION

FIG. 1 illustrates a side perspective view of a brush head for an electric toothbrush.

FIG. 2 illustrates a first side of the brush head for an electric toothbrush.

FIG. 3 illustrates a second side of the brush head for an electric toothbrush.

FIG. 4 illustrates a third side of the brush head for an electric toothbrush.

FIG. 5 illustrates a fourth side of the brush head for an electric toothbrush.

FIG. 6 is a top plan view of the brush head for an electric toothbrush; and,

FIG. 7 is a bottom plan view of the brush head for an electric toothbrush.

The broken lines shown in drawings are included for the purpose of illustrating unclaimed portions of the brush head for an electric toothbrush and environmental structure, and form no part of the claimed design.

1 Claim, 4 Drawing Sheets
